UNITED STATES PATENT OFFICE

117,551

DESIGN FOR A TRASH BURNER

Charles R. Blood, Sacramento, Calif.

Application March 8, 1939, Serial No. 83,432

Term of patent 14 years

To all whom it may concern:

Be it known that I, Charles R. Blood, a citizen of the United States, residing at Sacramento, in the county of Sacramento and State of California, have invented a new, original, and ornamental Design for a Trash Burner, of which the following is a specification, reference being had to the accompanying drawing, forming a part thereof, and in which:

I claim:

The ornamental design for a trash burner, as shown.

CHARLES R. BLOOD.
